[57] CLAIM

The ornamental design for an inhaler, as shown and described.

DESCRIPTION

FIG. 1 is a perspective view illustrating the front, left side and top of my new design for an inhaler;

FIG. 2 is a perspective view similar to FIG. 1 illustrating the front, left side and top with the cover in an open position rotated from its position in FIG. 1;

FIG. 3 is a right side elevational view;

FIG. 4 is a front elevational view;

FIG. 5 is a top plan view of my device;

FIG. 6 is a left side elevational view;

FIG. 7 is a rear elevational view; and,

FIG. 8 is a bottom plan view of my new design.
